Figure 1 is a front view of a refrigerator cabinet showing my new design;

Figure 2 is a top view thereof;

Figure 3 shows one of two similar sides of the refrigerator cabinet;

Figure 4 is an enlarged fragmentary sectional view of a part of the face of the refrigerator cabinet door taken on the line 4—4 of Figure 1; and,

Figure 5 is an enlarged fragmentary sectional view in another direction along that part of the face of the refrigerator door shown in Figure 4 and is taken on the line 5—5 of Figure 1.

The dominant feature of my design resides in the configuration of the recessed portion in the face of the refrigerator cabinet door.

I claim:

The ornamental design for a refrigerator cabinet, as shown and described.
